MULTIPLE CYLINDER FLUID MOTOR OR
COMPRESSOR OF THE RADIAL PISTON
TYPE

Lester Sejarto, Richmond Hill, N. Y.

Application July 9, 1943, Serial No. 493,980

6 Claims. (Cl. 121—121)

1

This invention relates to motors of the pressure fluid actuated type and fluid compressors. An object of the invention is to provide a compact and practical fluid motor structure suitable for support on the movable work head of a machine tool for transmitting power directly thereto. Another object of the invention is to provide a motor or compressor structure in which a plurality of cylinders and pistons are radially disposed in a common plane with a rotary valve operatively interposed internally between the plane in which the pistons operate and the intake and exhaust ports of the motor or compressor. A further object of the invention is to provide apparatus for transmitting power to a shaft, and by which means the shaft may be pneumatically operated at variable rates of speed effective for the most efficient performance of different kinds of work, for example, where the speed of the tool rotated by the motor is, in this respect, of the utmost importance.

Another object of the invention is to provide for the transmission of power to drive a machine tool at variable rates of speed and where, for lack of space, it is not practical to employ belting or gears to obtain variations in the speed of the tool.

An advantageous feature of the invention resides in a motor constructed to be mounted on the head of an ordinary milling machine in vertical alignment therewith, and adapted to be directly supplied with the output of a remote compressor, preferably of like design, driven from a source of energy such as an electric motor, and so that the pneumatic motor will be resiliently responsive to changes in the power increment and decrement of such source of energy. The motor of this invention is especially advantageous for use as a driving means for metal working machinery, and being compact, renders the machine tool head more readily adaptable to types of work where internal operations are to be performed and during which the head of the machine requires to be manipulated.

The flow of power is controlled automatically and instantly by the building up of fluid pressure such as air in the motor when the work load is applied to a tool driven thereby, and by the diminishing of said air pressure when such load is relieved, there being no pressure fluid storage reservoir other than the conduit connecting the motor and compressor.

Other features and advantages of the invention will be hereinafter described and claimed.

2

The invention will be more fully understood by reference to the drawings forming a part of this specification, and in which drawings,

Fig. 1 is a plan view of a pneumatic motor embodying the invention.

Fig. 2 is a side elevation of the same showing in dot and dash lines a portion of a flexible air conduit applied to the inlet port of the motor.

Fig. 3 is a vertical section taken on the line 10—3—3 of Fig. 1.

Fig. 4 is a horizontal section through the pistons of the motor indicated by the line 4—4 of Fig. 3.

Fig. 5 is a similar section taken on the line 15—5—5 of Fig. 3.

Fig. 6 is a fragmentary vertical section partly in elevation, showing a portion of Fig. 3 with the pistons and rotary valve in a preceding position of 90 degrees to that shown in Figs. 3, 4 and 5.

Fig. 7 is a horizontal section on the line 7—7 of Fig. 6.

Fig. 8 is an elevation partly in section, of the rotary valve of the motor looking in the direction of the arrow 8 of Fig. 5.

Fig. 9 is a plan view of the rotary valve shown in Fig. 3.

Referring now to the drawings and particularly to Fig. 3, the motor 10 consists of a supporting sleeve 11 within which there is journaled at 12 one end of a shaft 13. Cylinder blocks 14, radially disposed outwardly from sleeve 11 and integral therewith, are bored to receive bushings 15 which constitute cylinders for horizontally reciprocable pistons 16 having connecting rods 17 commonly pivoted on a stud 18 projecting eccentrically and upwardly from a crank disk 19 formed integrally with the shaft 13.

Above the group of horizontally and radially disposed cylinders is a vertically mounted intermediate member 20 the lower end 21 of which is fitted snugly within a cylindrical opening 22 formed in the body 14 uniting said cylinder blocks, and secured thereto by bolts 23 passing through an annular flange 24 forming a part of member 20. Above member 20 there is a head member 24 secured by bolts 25. Member 24 is provided with an upper terminal stem 26.

Each cylinder block 14 is provided with a port 27 therethrough. A central cylindrical crank case chamber 43 houses the crank disk 19. A rotary valve 29, which serves as a distributor or distributing valve for the motor, is mounted above the plane of the piston and cylinder assembly. It consists of a hollow cylindrical member

31, and an upwardly extending stem member 32, secured together in any suitable manner so long as a chamber 33' exists therebetween. These parts are shown herein as secured by a flange 32' overlying member 31, and a boss 33 fitted tightly in said member. Member 31 has a boss 34 rising from its bottom wall into chamber 33', and which is bored eccentrically at 35 to receive the upper extremity of the stud 18. Rotary valve 29 is journaled in bearings 36 and 37 mounted in a spacing sleeve 38 tightly fitted in a central opening through member 20. When the crank disk 19 is rotated by the pistons 16 in a manner hereinafter described, the stud 18 will rotate the valve 29.

The outer end of each cylinder block is sealed by a cap 40 secured to it by bolts 42, and having a slot 40' formed on its inner face to provide a passageway between the respective outer ends of the cylinders 15 and ports 27. Ports 28 through the lower end 21 of member 20 are in registration with the ports 27, and in conjunction therewith serve for both the admission of a pressure fluid, such as air to, and the exhaust of the same from the outer end of cylinders 15 during the rotation of the valve 29.

Member 20 has a cylindrical chamber 44 at its upper end, and the lower end 21 is hollow and cylindrical, closely embracing and surrounding member 31 of the valve 29, and providing for clearance above the top of the flange 32' to form a cylindrical chamber 45. Ports 46 connect the chambers 44 and 45. Stem member 32 has a central longitudinal passageway 47 therethrough, and head member 24 has a port 47', which afford communication vertically between chamber 33' and an exhaust port 48 in a cylindrical reversing valve core 49 adapted to be oscillated by a handle 50 in a circular opening 52 extending transversely through the upper end of head member 24 adjacent the terminal stem 26 thereof. Port 48 leads into a port 53 passing through valve core 49 to atmosphere.

An arcuate port 54 extends partially around port 53, and has outlets 55, 56 and 57 spaced apart 90 degrees along the circumference of valve core 49. Stem 26 has an opening 58 therethrough leading to the circular opening 52, and member 24 has a port 59 leading from the chamber 44 to the said circular opening at a point 90 degrees from the intersection of port 58 with said opening 52.

The rotary valve 29 for timing the operation of the pistons 16 is provided with diametrically opposed peripheral portions 60 which engage the inner wall of the lower end 21 of member 20, and operate to successively open and close the correspondingly opposed ports 28 during the rotation of the valve 29. Between the portions 60 member 31 is cut away circumferentially to provide an arcuate opening 61 which opens at the top into chamber 45, and with which it is always connected. Directly opposite the cut out portion forming the opening 61 member 31 is slotted at 62 between portions 60, and through to chamber 33', and which is effective to connect ports 27-28 to passageway 47 by means of the chamber 33' commonly open to said ports and passageway.

In the following exemplary consideration of the operation of the apparatus described, it will be understood that air is referred to as the pressure fluid merely by way of illustration, and it will be apparent that the apparatus may be operated by use of other pressure fluids normally

resorted to in the functioning of a fluid motor or compressor.

It will now be apparent that when air under pressure enters port 58 it will pass through port 59 to chamber 44, and on to chamber 45 through ports 46. Assuming the motor parts to be in the position shown in Figs. 3, 4 and 5, air from chamber 45 will enter opening 61 in valve 29, and since that opening is now opposite one of the sets of ports 27-28 as shown in Fig. 5, the piston 16 of the corresponding cylinder shown in Fig. 4, will be moved in the direction of the arrow 70, and stud 18 will be rotated clockwise. Stud 18 will rotate valve 29 in a similar direction, and the next set of ports 27-28 in advance will be uncovered and brought into registration with opening 61 so that a corresponding piston will be actuated in the direction of the arrow 71 in Fig. 4. In the meantime the slot 62 now in registration with another one of the sets of ports 27-28 will provide for the exhaust in front of a corresponding piston moving in the direction of the arrow 72.

It will thus be seen that air entering or being exhausted through ports 27-28 will first enter through port 58 and finally leave through port 53, and will successively operate the pistons to drive shaft 13. Should it be desired to reverse the direction of rotation of shaft 13 the reversing valve core 49 may be moved a quarter turn clockwise by turning handle 50, as viewed in Fig. 2, away from contact with stop 13 and against stop 14. This will change port 48 into registration with port 59, outlets 55 and 57 of port 54 into registration respectively with ports 58 and 47', the outlet 56 then being closed by the walls surrounding valve core 49. Following this procedure air from inlet port 58 will now pass through outlet 55 into port 54 and thence through outlet 57 to passageway 47' which becomes an inlet instead of an exhaust passageway as heretofore. Should the parts be in the position shown in Fig. 4, the direction of the arrow 72 would be reversed and stud 18 would be turned oppositely or counter-clockwise.

It will now be seen that a very compact motor structure has been devised with effective internal means for timing the operation of the pistons, and in which the initial intake and exhaust ports 58 and 53 function continually as such, but in which the various air ports and passageways will be readily interchangeable to function for inlet or exhaust purposes with a corresponding change in the direction of rotation of the motor 10 and its shaft 13.

It will thus be apparent that the invention includes within its scope a fluid actuated motor or compressor involving a drive shaft adapted to be actuated by the reciprocation of the radially positioned pistons in their cylinders, when the apparatus is functioning as a motor, and adapted to actuate said pistons when the apparatus is operated as a compressor. The rotary valve functions as a distributor positioned proximate to the cylinders, and providing inlet and discharge ports coordinated with the cylinder ports for conducting high and low pressure fluid to and from said cylinders. The distributor valve is desirably provided with a hollow valve stem functioning as a conduit between the body portion of said distributor, adjacent one end of the stem, and a reversing valve is coordinated with the opposite end of the valve stem. Effectively the reversing valve may be in essentially superimposed position relative to the said hollow valve stem,

Supplementary to this valve stem conduit, another conduit extends between the reversing valve and the body portion of the distributor valve. The reversing valve expediently comprises a separate fluid inlet and an outlet for the motor, with separate conduit means respectively in communication with said inlet and said outlet. By rotating the reversing valve core 90°, the inlet conduit is in communication with the hollow valve stem conduit, while the outlet conduit is in communication with the supplementary conduit extending between the reversing valve and the body portion of the distributor valve. Alternatively the said inlet conduit may be positioned in communication with said supplementary conduit, while the outlet conduit of the reversing valve is simultaneously brought into communication with the hollow valve stem conduit. All of the aforementioned means are compactly associated in a casing or housing.

Various modifications of the invention might be employed for corresponding adaptations to other useful purposes within the scope of the invention claimed. While the invention is described in accordance with a preferred structural embodiment, it is obvious that changes and modifications may be made in the details of construction and in the combination and arrangement of parts without departing from the spirit of invention as defined in the following claims.

I claim:

1. In a fluid actuated motor comprising radial cylinders and pistons reciprocable therein, a central crank shaft, a stud secured eccentrically to the end of said shaft, a rotary valve, and a reversing valve, said rotary valve being journaled within said motor and engageable with said stud so as to be driven thereby, said rotary valve comprising a cylindrical body member and a cover member secured together and having a chamber therebetween, said cover member having a port therethrough opening into said chamber and leading to the reversing valve, and ports from said rotary valve for controlling the operation of said motor, said motor having an inlet port leading through the reversing valve to the exterior of the rotary valve, the circumferential outer surface of the rotary valve body member constituting a valve face provided with an opening extending partially around the same always in communication with said inlet port of the motor, and a diametrically opposite opening leading to said chamber, said motor having an exhaust port and the reversing valve being adapted to operate between the same and said inlet port, whereby said motor may be reversed by altering the position of said reversing valve relative to said ports.

2. A fluid actuated motor comprising radial cylinders and pistons reciprocable therein, a rotary distributor valve operatively associated with said pistons and actuated thereby, said distributor valve comprising a body portion and a hollow valve stem coordinated with said body portion and adapted for conducting fluid relative thereto, said cylinders having ports for fluid admission and exhaust, a reversing valve, and a housing enclosing the said designated means of the motor, said reversing valve being positioned in correlated association with the end of said hollow valve stem opposite the body portion of said distributor valve, another conduit within said housing extending between said reversing valve and the body portion of said distributor valve, said distributor valve providing inlet and discharge ports

coordinated with said cylinder ports for conducting high and low pressure fluid to and from said cylinders.

3. A fluid actuated motor or compressor comprising radial cylinders and pistons reciprocable therein, a distributor valve operatively associated with said pistons, said distributor valve comprising a body portion and a hollow valve stem coordinated with said body portion for conducting fluid relative thereto, said cylinders having ports for fluid admission and exhaust, a reversing valve, said reversing valve being positioned in correlated association with the end of said hollow valve stem opposite the body portion of said distributor valve, another conduit extending between said reversing valve and the body portion of said distributor valve, said distributor valve providing inlet and discharge ports coordinated with said cylinder ports for conducting high and low pressure fluid to and from said cylinders.
4. A fluid actuated motor comprising radial cylinders and pistons reciprocable therein, a rotary distributor valve operatively associated with said pistons and actuated thereby, said distributor valve comprising a body portion and a hollow valve stem coordinated with said body portion for conducting fluid relative thereto, said cylinders having ports for fluid admission and exhaust, a reversing valve having a fluid inlet and a fluid outlet for said motor and separate conduits in said reversing valve for said inlet and said outlet, and a housing enclosing the said designated means of the motor, said reversing valve being positioned at the end of said hollow valve stem opposite to the said rotary distributing valve body portion, another conduit within said housing extending between said reversing valve and the body portion of said distributor valve, said reversing valve being adapted for alternatively positioning said inlet conduit in communication with said hollow stem conduit while said outlet conduit is in communication with said other fluid conduit and for positioning said inlet conduit in communication with said other fluid conduit while said outlet conduit is in communication with said valve stem conduit, said rotary distributor valve providing inlet and discharge ports coordinated with said cylinder ports for conducting high and low pressure fluid to and from said cylinders.
5. In a pressure fluid actuated motor or compressor, a drive shaft, a plurality of cylinders radially positioned relative to said drive shaft, pistons reciprocable in said cylinders, means for operatively coordinating said shaft with said pistons for correlated actuation, a rotary distributing valve proximate to and coordinated with said cylinders and adapted for correlated movement with and actuation by said shaft, a reversing valve comprising a separate fluid inlet and outlet and separate conduit means in communication with said inlet and said outlet, said distributing valve having a body portion and a hollow stem providing a conduit between said body portion and the reversing valve, said valve body portion having inlet and discharge ports correlated with said cylinders, another conduit means substantially parallel to said valve stem providing communication between said reversing valve and the body portion of said distributing valve, said reversing valve being adapted for alternatively positioning said inlet conduit in communication with said hollow valve stem conduit while said outlet conduit is in communication with said

other conduit and for positioning said inlet conduit in communication with said other conduit while said outlet conduit is in communication with said hollow valve stem conduit.

6. In a pressure fluid actuated motor or compressor, a drive shaft, a plurality of cylinders radially positioned relative to an end of said drive shaft, pistons reciprocable in said cylinders, means for operatively coordinating said shaft with said pistons for correlated actuation, a rotary distributing valve proximate to and coordinated with said cylinders and adapted for correlated movement with and actuation by said shaft, a reversing valve comprising a separate fluid inlet and outlet and separate conduit means in communication with said inlet and said outlet, said distributing valve having a body portion and a hollow stem providing a conduit between said body portion and the reversing valve, said valve body portion having inlet and discharge ports correlated with said cylinders, a housing for said cylinders, distributing valve and reversing valve, another conduit means substantially parallel to said valve stem within said housing, providing communication between said reversing valve and the body portion of said distributing valve, said

reversing valve being adapted for alternatively positioning said inlet conduit in communication with said housing conduit while said outlet conduit is in communication with said hollow valve stem and for positioning said inlet conduit in communication with said hollow valve stem while said outlet conduit is in communication with said housing conduit.
